UNITED STATES PATENT OFFICE

ALBERT C. GRUNWALD, OF RIVER FOREST, ILLINOIS, ASSIGNOR TO PRECISION METAL WORKERS, OF CHICAGO, ILLINOIS, A CORPORATION OF ILLINOIS

DESIGN FOR AN ASH RECEPTACLE

Application filed September 6, 1930. Serial No. 36,886. Term of patent 14 years.

To all whom it may concern:

Be it known that I, ALBERT C. GRUNWALD, a citizen of the United States, residing at River Forest, Cook County, Illinois, have invented a certain new, original, and ornamental Design for an Ash Receptacle of the Pedestal Type, of which the following is a specification, reference being had to the accompanying drawing, forming a part thereof.

The single view of the drawing is a front and slightly perspective view of the ash receptacle embodying my new design.

I claim:

The ornamental design for an ash receptacle as shown.

In witness whereof, I hereunto subscribe my name this 2nd day of September, 1930.

ALBERT C. GRUNWALD.
